Primary Examiner — Randall Gholson(74) *Attorney, Agent, or Firm* — Mark E. Bandy; Rankin, Hill & Clark LLP(57) **CLAIM**

The ornamental design for a wrench, as shown and described.

DESCRIPTION

FIG. 1 is a rear left perspective view of a wrench.

FIG. 2 is a left side view of the wrench of FIG. 1.

FIG. 3 is a right side view of the wrench of FIG. 1.

FIG. 4 is a rear plan view of the wrench of FIG. 1.

FIG. 5 is a front plan view of the wrench of FIG. 1.

FIG. 6 is a top end view of the wrench of FIG. 1; and,

FIG. 7 is a bottom end view of the wrench of FIG. 1.

The dashed lines are for illustrative purposes only showing environmental subject matter and form no part of the claimed design.

1 Claim, 7 Drawing Sheets# US D748,958 S
